UNITED STATES PATENT OFFICE.

JOSEPH E. JONES, OF MOUNT WASHINGTON, MISSOURI.

OIL BURNER.

Application filed June 11, 1923. Serial No. 644,639.

To all whom it may concern:

Be it known that I, JOSEPH E. JONES, a citizen of the United States, and resident of Mount Washington, county of Jackson, 5 State of Missouri, have invented a certain new and useful Improvement in Oil Burners, of which the following is a complete specification.

This invention relates to oil burners and 10 my object is to produce an efficient and economical oil burner, and connections whereby the flow of oil may be positively controlled from a remote point without danger of completely shutting off the flow.

15 Another object is to provide means whereby the accidental complete closure of the feed valve may be positively guarded against.

20 A further object is to provide a burner which is readily adjustable as to height to accommodate particular furnaces.

With the objects named in view the invention consists in certain novel and useful features of construction and organization of 25 parts as hereinafter described and claimed; and in order that it may be fully understood, reference is to be had to the accompanying drawing, in which:

Figure 1 is a side elevation of an oil 30 burner embodying the invention;

Figure 2 is a section on the line II—II of Figure 1; and

Figure 3 is an enlarged section on the line III—III of Figure 2.

35 In the said drawing, where like reference characters identify corresponding parts in all of the figures, 1 represents an oil supply pipe leading from any convenient source of supply and controlled by a hand-valve 2.

40 The pipe 1 will ordinarily extend within the ash door of a furnace and is in communication with a pair of pipes 3 extending upwardly through the grate of the furnace into the fire box, not shown. The assembly thus described is supported by a pair of plates 4 provided with leveling feet 5 in their extremities, whereby the burner may be readily and easily leveled as common in the art. It 45 will be readily apparent that the length of the pipes 3 may be easily varied to accommodate any particular type or size of furnace by making them in sections connected together by unions 3a.

The vertical pipes 3 are threaded near their 50 upper ends through bosses 6 formed on the underside of a fire plate 7, and are engaged

with the opposite ends of an inverted U-shaped generator 8. Communicating with the vertical center of the generator is a short pipe section 9 which is axially connected to a shallow gas-superheating chamber 10. Leading from the upper part of the side wall of the superheater is a gas pipe 11 which at its lower end is connected to the stem of a T-coupling 12 having its head 60 in vertical alinement with the center of the superheater and supported by the plate 7.

Secured in the upper end of the head of the T-coupling is a burner tip 13 formed internally with a conical bore 14, and communicating with the other end of said head of the T-coupling is a short pipe section 15 extending downwardly through an opening 16 formed centrally of the plate 7.

The T-coupling and its connections are 75 securely maintained in position on the plate 7, by means of a nut 17 threaded on the pipe 15 and in abutment with the underside of said plate. The pipe 15 is closed at its lower end by any suitable packing 18 held 80 in position by a packing nut 19. Slidably mounted in the pipe 15 is the stem 20 of a conical valve 21, said valve being adapted to enter the conical bore 14 of the burner tip 13, it being noted in this connection that 85 the stem 20 is reduced as at 22 to allow of a certain flexibility of movement of the valve 21 in finding its seat, and also to provide an enlarged chamber 23 for the reception of the gas, as will be readily understood.

90 The lower end of the stem 20 is pivotally connected to a link 24 having adjustable connection at 25 with an arm 26 rigidly secured by a clamping nut 27 to a rotatable shaft 28. The shaft 28 is journaled in a pair of 95 hangers 29 clamped by means of clamping screws 30 to the vertical pipes 3, and said shaft extends outside the furnace and keyed to the end thereof is an operating lever 31 provided with a suspended weight 32, it 100 being evident in this connection, that the weight 32 will tend to rotate the shaft 28 which, through its connections above-described, will close the slide valve 21 and shut off the flow of oil.

105 Connected to the lever 31 is an operating chain 33 which may be manually or automatically controlled to open the valve by an upward pull imparted to the chain, which may lead, if desired, to any floor above the 110 basement. In order to prevent the accidental full closure of the valve 21, the le-

ver 31 is provided with a pivoted leg 34 which, through contact with the floor, will limit the downward movement of the end of the lever and consequently limits the closure of the valve. The leg 34 is provided with an adjustable foot 35 whereby the limit of closing movement may be readily regulated.

In the operation of the burner, paper or 10 the like is placed in the fire plate 7 and a quantity of oil is allowed to overflow the burner tip and saturate such material. The flow of oil is now shut off and the material contained on the fire plate is ignited. 15 This burning material will soon gasify the oil contained in the superheater and its connections. As soon as a quantity of gas has been generated, the valve is again opened to permit the gas to escape from the top to ignite, and this burning gas impinging of the 20 superheater and burner will quickly gasify all of the oil in the superheater and a certain proportion thereof standing in the generator as common in the art. 25 It will be evident that thereafter the quantity of oil consumed by the burner may be readily regulated through opening movements imparted to the valve 21 by means of the pull chain 33 and gravitational closing 30 movements imparted by the weight 32. It will be noted that the bottom of the superheater 10 is slightly concave and centrally thereof is formed with a shallow conical connection having its apex in alignment 35 with the jet orifice of the burner tip so as

to deflect the flame radially outward in all directions, the concave surface of the superheater having a tendency to cause the flame to spread horizontally outward sufficiently to impinge against the walls of the fire pot 40 so as to obtain maximum benefit from the heat units and thereby affect conservation of fuel in the operation of the burner.

From the above description it will be apparent that I have produced an oil burner 45 of the character described which possesses all of the features of advantage set forth as desirable, and while I have described and claimed the preferred embodiment of the same, I reserve the right to make all changes 50 properly falling within the spirit and scope of the appended claim.

I claim:

In an oil burner, a supply pipe, a pair of vertical stand pipes leading upwardly therefrom, an inverted U-shaped generator communicating with the stand pipes, a superheater between the legs of the generator and communicating at its upper side with the overlying part of the generator, a fire plate 55 supported on the stand pipes below the generator, a coupling mounted on the central portion of the fire plate vertically below the superheater and provided with a gas nozzle, a vapor pipe connecting the superheater 60 with the nozzle, a slide valve in the nozzle, and means for adjusting said valve.

In witness whereof I hereunto affix my signature.

JOSEPH E. JONES.
